(57) **CLAIM**

The ornamental design for a cycle handle bar, as shown and described.

DESCRIPTION

FIG. 1 is a perspective view of a cycle handle bar showing our new design, with broken lines illustrating environmental structure and forming no part of the claimed design; FIG. 2 is an enlarged front view thereof;

FIG. 3 is an enlarged left-side view thereof, with the right-side view being a mirror image thereof; FIG. 4 is an enlarged top view thereof;

FIG. 5 is an enlarged bottom view thereof; and, FIG. 6 is an enlarged rear view thereof.
